DESIGN FOR A PEN STAND

Edward Kanter, Cleveland Heights, Ohio

Application August 14, 1933, Serial No. 49,014

Term of patent 7 years

To all whom it may concern:

Be it known that I, Edward Kanter, a citizen of the United States, residing at Cleveland Heights, in the county of Cuyahoga and State of Ohio, have invented a new, original, and ornamental Design for a Pen Stand, of which the following is a specification, reference being had to the accompanying drawing, forming part hereof, wherein Fig. 1 is a top plan view and Fig. 2 is a side elevation of a pen stand showing my new design.

I claim:—

The ornamental design for a pen stand substantially as shown.

EDWARD KANTER.
